United States Patent Office

Des. 191,211
Patented Aug. 29, 1961

191,211

GOLF PUTTER HEAD

Lee M. Forest, Hawthorne, Calif., assignor to Standard
Tool & Die Co., Los Angeles, Calif., a partnership

Filed Mar. 1, 1961, Ser. No. 64,107

Term of patent 14 years

(Cl. D34—5)

FIG. 1.

FIG. 2.

FIG. 3.

FIGURE 1 is a view in perspective of a golf putter head showing my new design with a fragmentary broken line showing of a shaft for illustrative purposes only;

I claim:

The ornamental design for a golf putter head, as shown and described.
